CLAIM

The ornamental design for an industrial robot, as shown and described.

DESCRIPTION

FIG. 1 is a front side view of an industrial robot.

FIG. 2 is a rear side view of the industrial robot shown in FIG. 1.

FIG. 3 is a left side view of the industrial robot shown in FIG. 1.

FIG. 4 is a right side view of the industrial robot shown in FIG. 1.

FIG. 5 is a top side view of the industrial robot shown in FIG. 1.

FIG. 6 is a bottom side view of the industrial robot shown in FIG. 1.

FIG. 7 is a rear left side perspective view of the industrial robot shown in FIG. 1.

FIG. 8 is a rear right side perspective view of the industrial robot shown in FIG. 1.

FIG. 9 is a front right side perspective view of the industrial robot shown in FIG. 1; and,

FIG. 10 is a front left side perspective view of the industrial robot shown in FIG. 1.

1 Claim, 10 Drawing Sheets
